UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

CENTERING OR POSITIONING MECHANISM FOR TYPE CASTING AND COMPOSING MACHINES.

1,079,321.

Specification of Letters Patent.

Patented Nov. 25, 1913.

Application filed October 26, 1912. Serial No. 727,951.

To all whom it may concern:

Be it known that we, JOHN SELLERS BANCROFT and MAURITZ C. INDAHL, citizens of the United States, and residents of Philadelphia, in the county of Philadelphia and State of Pennsylvania, have invented certain new and useful Improvements in Centering or Positioning Mechanism for Type Casting and Composing Machines; and we do hereby declare the following to be a full, clear, and exact description of the same, reference being had to the accompanying drawings, forming part of this specification, and to the figures and letters of reference marked thereon.

This invention relates to the class of automatic type casting and composing machines in which a plurality of spaced matrices representing different characters are operated upon by a centering or positioning mechanism to selectively present individual matrices opposite a mold and in register therewith. In commercial machines of this variety two such centering mechanisms are usually employed for controlling motions in relatively transverse directions, and each is equipped with a signal responsive gage whose pitch or measure corresponds with or is proportional to the spacing of the matrices in the direction of motion controlled thereby, the arrangement being such that the die case or other performing member is operated on what is sometimes designated the point-to-point system, owing to the fact that the adjusted member is shifted directly from one of a series of stations to any other in said series, without having to be returned each time to a zero or initial position. Accuracy, speed and capacity are prime factors in the success of such machines and inertia, the stumbling block, and in the compromise effected between these antagonistic elements the weight and dimensions of the die case with its contained matrices is reduced to a minimum consistent with the requirements of the machine. Hence it is that the commercial machine, being specially designed to deal with the more popular or commonly used type sizes—twelve point and under—has its die case proportioned to accommodate a maximum of two hundred and twenty-five matrices arranged in fifteen parallel rows of fifteen matrices each. The matrices are uni-

formly spaced in each direction on a scale of two tenth inch, thus limiting the area available for any given character to a square two tenths inch on each side. These dimensions are inadequate for the larger size characters pertaining to fonts of fourteen point and over, to accommodate which either the capacity of the die case for numbers must be greatly reduced, or special machines or equipments based upon the new measure must be provided. An example of such accommodation is to be found in Patent No. 980,959, dated January 10, 1911, wherein provision is made for increasing the size of the matrices in units of the normal, that is to say, by increments of two tenths of an inch in either or both directions. This unit is necessary in order that the signal controlled primary gage whose pitch or measure is fixed at two tenths inch may be made to work in harmony with both the normal and abnormal matrices. It so happens, however, that this unit is in excess of the requirements of some of the larger point sizes, hence unnecessarily diminishes the capacity of the die case and it is the purpose of the present invention to overcome in a measure this defect by increasing the capacity of the machine in this respect without in any degree interfering with the action of the machine in the performance of its normal functions in dealing with matrices of normal or standard dimensions.

To these ends the invention consists in providing the centering mechanism with a supplemental or auxiliary gaging means whose pitch or measure differs from yet harmonizes with the signal controlled gaging devices so that the latter may be employed for designating either normal or abnormal matrices and centering them opposite the mold.

The invention also includes minor features of construction and arrangement the particulars whereof are pointed out in the claims.

In the accompanying drawings illustrating a preferred form of embodiment of said invention, Figure 1 is a top plan view of a type casting and composing machine with the improvements applied thereto, the paper feeding, metal injecting and galley mechanisms being omitted for clearness. Fig. 2

2
is a partial horizontal section of the machine showing the additions and co-operating parts. Fig. 3 is a vertical section through the right hand adjusting mechanism of Fig. 1. Fig. 4 is a similar view, the parts being in a different position. Fig. 5 is a partial side elevation of the machine with the improvement shown applied thereto. Fig. 6 is a horizontal sectional view of the valve mechanism on the line α — α , Fig. 5. Fig. 7 is a vertical sectional view of one of the valve chambers with the actuating lever in elevation.

10 Like letters of reference in the several figures indicate the same parts.

The invention is illustrated in connection with the type casting and composing machine of Patent No. 625,998 dated May 30, 1899, with the improvements of Patent No. 20 749,149, dated Jan. 12, 1904 applied thereto.

It will suffice, for present purposes, to designate some of the principal elements of the prior patented machine, such as the die case 1, its carrier 2, and support 3; the centering pin lever 4 and the two centering mechanisms connected with and controlling the movements of the die case and its carrier, respectively, each of said mechanisms including a primary gage represented by fifteen serially arranged and equally spaced stop pins 5 or 5 $\times$ of which each, save that at one end of the series, is separately controlled by a piston and an air duct leading to one of a series of ports in the tracker bar (not shown) of the paper tower; a primary positioning mechanism comprising oppositely movable jaws 6 or 6 $\times$ one of which engages a stop pin when projected into its path and the other closes upon the engaged jaw; a 40 secondary gage or stop bar 7 or 7 $\times$ interposed between and brought to position by the closing jaws 6 or 6 $\times$; said stop bar being furnished with a series of teeth 8 or 8 $\times$ spaced to correspond with the spacing of the 45 matrices in the die-case and engaged by a locking bar 9 or 9 $\times$, the latter engaged by one of two levers 10 or 10 $\times$ acted on by one of a pair of springs 11 for advancing and by a cam controlled pusher 12 or 12 $\times$ for retracting said bolt, and a secondary positioning mechanism represented by oppositely movable jaws 13 or 13 $\times$, closing on stop bar 7 or 7 $\times$ and upon a translating device 14 or 14 $\times$, the latter coupled with the performing 50 member represented in this case by either the die case or its carrier. This is the normal equipment for dealing with a die-case containing fifteen rows of fifteen matrices each, the primary and secondary gages of 55 the positioning or centering mechanisms each being equipped with admeasuring devices for fifteen equally spaced stations. Whatever the unit of this measure it is obvious the signal responsive members of the 60 primary gage could only indicate stations 65

separated in units or multiples thereof. As hereinbefore stated the unit of measure adopted for the commercial machines and the matrices therefor is two tenths of an inch, while that of the matrix can, according to Patent No. 980,959, be increased to four tenths inch which is the next larger size matrix available.

For some of the larger fonts and under special circumstances less than a two unit increase in the size of the matrices in one or both directions will suffice to accommodate the character, and if a fractional increase can be made the capacity of the die case will be increased accordingly. Thus with the two unit abnormal matrices, but eight matrices can be associated in any one line or column, to wit, seven of two units and one of one unit, dimensions, whereas with a one half unit increase, which is ample for some of the larger point sizes, ten matrices of one and a half units dimensions can be associated together in a line or column whose normal measure, as indicated by the primary gage, is fifteen units in length.

In the example diagrammatically illustrated in Fig. 2, the die case is equipped with ten rows of matrices, whereof seven rows are arranged in fifteen equally spaced columns and the remaining three rows in ten equally spaced columns; otherwise stated, the matrices are all one and one-half units ($\frac{3}{5}$ inch) columnwise, those comprising each of seven rows, being one unit ($\frac{1}{5}$ inch) in width, and those of each of the three remaining rows being one and one-half unit ($\frac{3}{5}$ inch) wide.

It is obvious that the normal centering mechanism is incompetent to deal with such a die case (other than for effecting the adjustments pertaining to the lines of fifteen matrices each which correspond with the pitch or measure of the signal responsive gage) owing to the fact that the pitch or measure differs from the normal established by the primary and secondary gages. The problem thus presented involves the utilization of the signal responsive gaging mechanism for selectively effecting adjustments pertaining to two different series, the one normal to said gaging mechanism and the other varying therefrom in a predetermined degree; and the solution is found in the addition of an auxiliary positioning means for automatically varying the adjustments effected through the normal centering mechanism to accord with the spacing of the abnormal matrices. A form of auxiliary positioning mechanism suited to the purpose is shown, by way of illustration, as applied to and operating in conjunction with each of the stop bars 7, 7 $\times$, which latter, by their positions, determine the closing points of jaws 13 and 13 $\times$, respectively, and the resulting adjustments of the die case on inter-

secting lines. Said auxiliary positioning means is in the form of a rack 15 or 15^x formed on an extension of or otherwise suitably coupled with the corresponding stop bar or gage 7 or 7^x, and a positioning member or bolt 16 or 16^x guided on the frame and adapted to engage the inclined teeth of the rack for shifting the latter by an amount equal to the difference, if any, between the 10 position indicated in relation to the normal matrices and that occupied by the abnormal matrix to which the same signal responsive member is assigned.

As shown the teeth 17 of racks 15 and 15^x differ in pitch from the normal locking teeth 8 or 8^x in the proportion of ten to fifteen thus dividing the movements of adjustment as affected by each stop bar into ten equal intervals as compared with the fifteen represented by the normal teeth 8 or 8^x. It results from this arrangement that when either stop bar 7 or 7^x is adjusted to the positions indicated by its signal responsive gage, teeth 17 of its rack 15 or 15^x will be at times out 20 of register with positioning member 16 or 16^x, and if when so out of register the member 16 or 16^x, is advanced it will engage the inclined side of the nearest tooth 17 and operate thereon to shift and thus vary the 25 position of the stop bar to accord with the station in the auxiliary system represented by the interval between the engaged teeth. Thus with a layout such as indicated in Fig. 2 wherein the stations columnwise are 30 equally spaced but abnormal and the stations linewise are normal for seven lines and abnormal for the remaining three lines, the auxiliary positioning mechanism will be utilized for effecting columnwise adjustments, the normal centering mechanism for 35 seven lines and the auxiliary for the three remaining lines, the position of adjustment in either direction being primarily indicated and determined by the signal responsive members of the gages. In this instance, 40 where the auxiliary positioning means is applied to the stop bar, it is required that the action of the normal locking bar 9 or 9^x should be suspended when said auxiliary is 45 to be utilized for varying the position and that the action of the auxiliary positioning mechanism should likewise be suspended when normal adjustments are to be effected. Mechanism for selectively effecting these 50 actions is shown and will next be described.

Each positioning member 16, 16^x is provided with retracting means (represented by spring 18 or 18^x) and with projecting means (represented by piston 19 or 19^x, 55 working in a cylinder 20 or 20^x) the member 16 pertaining to the column or horizontal series of stations (Fig. 2) being connected directly to its piston 19 and the other, as matter of accommodation, indirectly connected to its piston 19^x through a lever 21.

Opposite lever 10 of the locking bar 9, pertaining to the horizontal positioning mechanism, (Fig. 2) is a motor in the form of piston 22 working in a cylinder 23; and connected through a link 24 and lever 25 with the locking bolt 9^x of the vertical positioning mechanism is, a similar piston 22^x working in a cylinder 23^x, the arrangement being such that when pressure is admitted to either cylinder it will overcome the propelling spring 11 of the corresponding locking bar 9 or 9^x and hold the latter out of contact with its stop bar 7 or 7^x.

Whenever a transfer from the normal to the auxiliary positioning mechanism is required to be made it is only necessary to admit pressure to the cylinder 23 or 23^x corresponding with the direction of movement to be controlled, thereby throwing locking dog 9 or 9^x out of action, and, at the proper point in the cycle, admit pressure to the cylinder 20 or 20^x, to advance the positioning member 16 or 16^x, and thereby shift the stop bar from the position directly indicated by the signal responsive gage to that indicated by the auxiliary gage acting in conjunction therewith.

Inasmuch as the adjustments or readjustments performed by the positioning members 16 and 16^x are supplemental or auxiliary to the adjustments directly produced by the normal signal responsive devices, it is necessary that they be performed in the interval between the action of said signal responsive means and the final seating of the selected matrix upon the mold; and when the spacing in either direction is not uniform but irregular, being in part normal and in part abnormal, as in the example illustrated herein, it is more convenient that automatic means be provided for effecting the transfer from the one system to the other. This can readily be accomplished by various mechanism of which a preferred form is illustrated and will now be described.

In a frame 35 detachably secured to the main frame of the machine is formed a pressure chamber 36 communicating through a pipe 37 with a source of air pressure, said pipe containing a control cock 38. Opening toward and into chamber 36 are two valves 40, 40^x, the stems whereof are engaged, respectively, by levers 41 and 42. The opposite arm of lever 41 is arranged to contact with the centering pin lever 4, and is advanced to contact therewith, when in action, by a pressure motor, preferably in the form of a piston 43 working in a cylinder 44, the latter communicating with the pressure supply, as by being connected to chamber 36, so that when the system is cut out by means of cock 38 lever 4 will be relieved of the added pressure. Lever 42 carries a movable interponent 46 in the form of a rod 47 working through a bearing in one

arm of said lever 42 in position to engage a shoulder 48 on lever 41, the arrangement being such that as lever 4 is moved to elevate the centering pin, levers 41, 42 will be operated to unseat the valves or open the passages controlled thereby, this action taking place during the opening movement of jaws 6, 6^x, after locating stop bars 7, 7^x, and before the closing movement of jaws 13, 13^x 10 on their stop bars, whereby the proper timing of the auxiliary positioning movement is insured.

Cylinders 20 and 23 are connected through a pipe 49 with a chamber in rear of valve 40^x, and, but for the fact that the abnormal series of movements affected by the positioning member 16^x pertaining to the vertical series of adjustments are uniform, a similar arrangement might be applied in 15 connection with valve 40; but inasmuch as this series, although abnormal, is uniform and in consequence thereof is used, when at all, to the exclusion of the normal adjusting series, cylinder 23^x is connected through 20 pipe 50 with pressure chamber 36, while cylinder 20^x is connected by pipe 49^x on the other side of valve 40. By this means when the auxiliary positioning mechanism is connected up for action the locking bolt 9^x of 25 30 the vertical adjusting mechanism, Fig. 2, will be locked out of action through pressure in cylinder 23^x instead of being withdrawn at each advance of the associated positioning member 16^x.

35 Where, as in the present case, both series of adjustments—normal and abnormal—are interchangeably employed, the shift from one to the other can be automatically effected through the agency of the companion 40 auxiliary positioning mechanism and it is for this purpose the movable interponent 46 is introduced. Rod 47 is connected to one arm of a lever 51 whose opposite arm carries a pivoted angular link 52. One arm of 45 link 52 carries a roller 53 adapted to ride upon stop bar 7 and the latter is recessed as at 54 to receive the toe of said link when the stop bar is adjusted to correspond with the lines of matrices of normal width. In the 50 example illustrated, wherein the first seven lines of matrices are operated on by the normal positioning mechanism for horizontal adjustment (Fig. 2) the slot or recess 54 pertaining to the vertical system terminates 55 lengthwise of the stop bar over the space covered by its movement for the first seven lines of matrices counting from the bottom in Fig. 2 and measured with relation to the toe of link 52. When the stop bar is located in any one of the seven stages or positions indicated, roller 53 will ride on the surface of the stop bar and the toe of said link will be projected into recess 54, which position will be maintained by a spring 55 60 acting on lever 51. Under these circum-

stances rod 47 will be shifted to clear shoulder 48 of lever 41 in consequence whereof lever 42 will not be engaged and valve 40^x remaining seated the auxiliary positioning devices pertaining thereto will not be 70 brought into action and the normal positioning devices for the horizontal movement will continue in action affording fifteen degrees of adjustment for the seven lines referred to. When, however, the movement of the stop bar is increased to cover any of the three upper lines of matrices, Figs. 2 and 3, the right end of recess 54 engaging the toe of link 52 will elevate the latter to the level of the surface of the stop bar, 80 thereby tilting lever 51 to project the interponent into the path of shoulder 48 so that upon the next movement of lever 4 valve 40^x will be moved to admit pressure to cylinders 20, 23, and thus apply the auxiliary positioning mechanism in effecting horizontal adjustment of the die case in connection with either of the three upper lines of matrices indicated in Fig. 2. Upon the return of stop bar 7^x to the territory covered 90 by the first seven lines of matrices, link 52 will again enter recess 54 withdrawing interponent 46 and restoring the control of the normal centering devices.

In the example illustrated, wherein the ratio between the abnormal and normal units of measure is as one and a half to one the alternative admeasuring devices are so correlated as that when the performing member, *i. e.*, the stop bar, is brought to the position indicated by the first or fixed pin of the primary gage to register the first in the normal series of fifteen units, the positioning member 16 or 16^x will stand midway between the first and second teeth 17 of rack 15 or 15^x to establish the first of the ten units of the abnormal or auxiliary system. As thus arranged when the auxiliary system is connected up and in action the second, fourth, fifth, seventh, eighth, tenth, 105 eleventh, thirteenth and fourteenth stop pins, counting the fixed pin as one, will locate the stop bar in proper relation to positioning member 16 to cause it, when operating, to effect adjustments corresponding 110 with the second, third, fourth and so on up to the tenth degree, respectively, in the abnormal or auxiliary system.

A brief summary will suffice to explain 115 the operation.

When a die case containing only matrices of normal dimensions are employed control cock 38 is closed to cut out the auxiliary system and the machine operates in the usual well known manner. When a die case 125 equipped with the abnormal sized matrices is applied to the machine cock 38 is opened with the result that the locking bar of the centering mechanism pertaining to the vertical series of positions, Fig. 2, is locked 130

out of action through the admission of pressure to cylinder 23^x. The position of the die case necessary to bring any one of the matrices into position above the mold measured 5 on the scale of the abnormal system being indicated by a signal bringing into action, i. e., projecting the appropriate stop pins, the stop bars are positioned accordingly, thereby effecting a preliminary location of 10 said stop bars in such relation to the auxiliary positioning members 16 or 16^x as that when the latter are projected, they will enter between the teeth 17 of the admeasuring racks 15 or 15^x and, if necessary, shift the 15 latter in one direction or the other in an amount corresponding to the difference between the station indicated by the stop pin and that indicated by the positioning member in its relation to the two adjacent teeth 20 of rack 15 or 15^x between which it is for the time being located. The projection of the positioning members is effected through the opening of valves 40, 40^x, or either of them accordingly as the auxiliary system is applied for effecting adjustments in one or the other or both directions.

Where both normal and abnormal adjustments are applicable to the movement in one direction, for example, horizontally in Fig. 30 2, selection is effected through link 52 and interponent 36 and the timing through levers 41 and 42.

Although illustrated herein in connection with a point-to-point centering mechanism 35 embodying both primary and secondary gaging and positioning mechanisms, according to Patent No. 625,998, the invention is not limited thereto, but is applicable to other forms of mechanism, such, for example, as 40 that disclosed in our application Serial No. 709,468, filed July 15, 1912, wherein the secondary gage is replaced by a movable member connected directly to the performing member, such as the die case, its carrier, etc., 45 and one of the positioning mechanisms herein shown, is entirely dispensed with.

Having thus described our invention, what we claim as new and desire to secure by Letters Patent of the United States, is:

50 1. A type casting machine organized to receive and act upon a two-way movable die case provided with matrices uniformly spaced in the directions of movement of said die case and equipped with two centering mechanisms each provided with a signal controlled gage, a positioning mechanism and a movable member whose location is determined by said positioning mechanism, and in combination therewith, a die case equipped 55 with matrices uniformly spaced in one direction in a measure differing from that of the signal controlled gage pertaining to the same line of movement, and spaced in the other direction partly in the measure of the associated signal controlled gage and partly in

a measure differing therefrom, auxiliary gaging mechanism (one for each direction of movement of the die case) furnished with gaging members spaced to correspond with the spacing of the matrices in the direction of motion controlled thereby, means for coupling each of said auxiliary gaging mechanisms with the movable member of the corresponding centering mechanism, and means controlled by one centering mechanism for automatically bringing into action the auxiliary gaging mechanism of the associated centering mechanism. 70

2. A type casting machine equipped with duplex centering or positioning mechanisms, 80 each including a signal controlled primary gage, a positioning mechanism, a movable member whose position is determined by said positioning mechanism and associated gage and adapted to operate in conjunction with a two-way movable die case, the matrices whereof are spaced in two directions to accord with the pitch or measure of the primary gages, and in combination therewith, a die-case whose matrices are abnormally spaced relatively to the primary gages, gaging means auxiliary to the primary gages, and corresponding in pitch or measure with the spacing of the matrices, and controllable means for cutting into and out of action said auxiliary gaging means. 90

3. In a type casting machine equipped with duplex centering or positioning mechanisms each of the latter including a signal controlled primary gage, positioning mechanism, a movable member, locking means for retaining the movable member in adjusted position, and actuating devices common to said positioning mechanisms, and locking means, and in combination therewith, two 100 positioning plungers and complemental gaging members each of the latter coupled with one of the said movable members and having its gaging members spaced differently from the associated primary gage, means for suspending the action of said locking means, and controllable actuating devices for said positioning plungers and lock-suspending means whereby when either positioning plunger is brought into action the corresponding locking means are thrown out of action. 110

4. In a type casting machine provided with duplex centering or positioning mechanisms, each of the latter including a signal controlled primary gage, a positioning mechanism, a movable member controlled by said positioning mechanism, and actuating devices for said positioning mechanisms, and in combination therewith, two positioning 120 plungers and complemental gaging racks each of the latter coupled with one of said movable members and having teeth spaced to a different measure from the associated primary gage, and actuating devices for said 125 130

- 6
- positioning plungers, including selective means coupled with one of said movable members for bringing into action the positioning plunger pertaining to the other movable member.
5. In a centering or positioning mechanism provided with a signal controlled primary gage, and oppositely movable positioning jaws, and in combination therewith, 10 a stop bar located between and positioned by said jaws and provided with two sets of teeth differing in pitch or measure, a locking bar for engaging one set of said teeth for retaining the stop bar in any of the various positions of adjustments indicated by the primary gage, a positioning plunger co-operating with the teeth of the other set for readjusting the stop bar, and means for automatically suspending the action of the 15 locking bar and for actuating the positioning plunger after the stop bar has been adjusted to the position indicated by the primary gage.
6. In a centering or positioning mechanism for type casting machines, the combination of the following elements to wit: 20 two centering mechanisms each provided with a movable stop bar and a locking bar therefor; auxiliary gaging members each 25 coupled with a stop bar and provided with an opposed positioning plunger, the latter coupled with an actuating motor, a retracting motor for each locking bar, a valve controlling the admission of pressure to the motor of one positioning plunger; a valve controlling the admission of pressure to the other 30 positioning plunger and to the motor of the associated stop bar; a pressure supply communicating with said valves and with one 35 locking bar motor; and actuating mechanism for said valves including controlling devices acted upon by one stop bar for connecting up the valve of the positioning plunger of the other stop bar.
- 40 7. In a centering mechanism for type casting machines, the combination of the following elements, to wit: a plurality of centering or positioning mechanisms for effecting 45 adjustments on relatively transverse lines, each including a movable stop bar and associated locking bolt; two auxiliary gaging mechanisms each including a positioning plunger and a gaging rack, the latter coupled with the corresponding stop bar; a 50 cylinder and piston for each plunger; a cylinder and piston for each locking bar and operating to throw the latter out of action; a pressure supply communicating directly with the cylinder of one locking bar 55 and through a valved port with the cylinder of the other locking bar; valves controlling communication between said pressure supply and the cylinder of the plunger pistons; and timing mechanism for operating said 60 valves to admit pressure to said plunger and locking bar cylinders.
8. In a centering or positioning mechanism for type casting machines provided with two centering mechanisms each including a movable member whose positions of adjustment are determined through a signal responsive gage and retaining devices for said movable member including a locking bolt, and in combination therewith, the following elements, to wit: two auxiliary 65 gaging mechanisms each including a gaging member coupled with one of said movable members and an opposed positioning plunger; a piston for each plunger and locking bolt; and a valve mechanism controlling 70 said pistons.
9. In a centering or positioning mechanism provided with a signal controlled primary gage and oppositely movable positioning jaws, and in combination therewith, 75 a stop bar interposed between said jaws and provided with two series of teeth differing in pitch, a locking bar co-operating with one series of teeth to retain the stop bar in any one of the series of positions defined by the primary gage, a plunger co-operating with the other series of teeth, and controllable means for alternately suspending the action 80 of said locking bar and plunger to permit one or the other to be brought into action 85
- as required.
10. A centering or positioning mechanism including two signal controlled primary gages, each operating through separate positioning mechanisms to adjust one of two 90 movable members, individual locking means for each of said movable members operating to retain the latter in their adjusted positions, and actuating mechanism controlling 95 said positioning mechanisms and locking means, and in combination therewith, two auxiliary gaging mechanisms each coupled with one of said movable members, controllable means for cutting into and out of action the auxiliary gaging mechanisms, and 100 means coupled with the actuating mechanism of the first named positioning mechanism for timing the action of the auxiliary gaging mechanisms.
11. A centering or positioning mechanism 105 equipped with a signal controlled primary gage, a movable member, positioning means for said movable member controlled by the primary gage and automatic locking means for retaining the movable member in adjusted position, and in combination therewith, an auxiliary gaging mechanism of a pitch or measure different from that of the primary gage and operatively connected to 110 said movable member for re-adjusting the latter, and controllable means for connecting up the auxiliary gage and for suspending 115 the action of the aforesaid locking means.
- 120
- 125

12. In a centering or positioning mechanism including a signal responsive primary gage, a movable performing member, positioning means for setting said movable member from said gage, and means for locking said movable member in adjusted position, and in combination therewith, an auxiliary gaging mechanism of different pitch or measure from the primary gage, and operatively connected with said movable member to re-adjust the position of the latter, and controllable means for suspending the action of the aforesaid locking means when the auxiliary gaging mechanism is brought into play.
13. A type casting machine provided with a plurality of centering or positioning mechanisms, each including a signal controlled primary gage, a secondary gage, and primary and secondary positioning mechanisms, and in combination therewith, a plurality of auxiliary gaging mechanisms each including a plunger and an opposed gaging member, the latter coupled to one of the secondary gages and having a pitch or measure differing from that of the associated primary gage, and automatic means for actuating the plungers in timed relation to their respective primary gages.
14. A type casting machine provided with a plurality of centering or positioning mechanisms each including a primary or signal controlled gage, a secondary gage, and primary and secondary positioning mechanisms, and in combination therewith, a plurality of auxiliary gaging mechanisms each coupled with the secondary gage of one of said centering or positioning mechanisms and including a toothed member the pitch or measure whereof differs from the associated signal controlled gage, and a coöperating plunger.
15. A type casting machine provided with a plurality of centering or positioning mechanisms each including a signal controlled primary gage, a primary positioning mechanism, a secondary gage and a secondary positioning mechanism, and in combination therewith, a plurality of auxiliary gaging mechanisms, each connected to one of the secondary gages and differing in pitch or measure from the associated signal controlled primary gage.
16. A type casting machine provided with a centering or positioning mechanism including a primary signal-responsive gage, a primary positioning mechanism, a secondary gage and a secondary positioning mechanism, and in combination therewith, an auxiliary gaging mechanism including a rack coupled with the secondary gage and provided with a series of teeth, the spacing whereof differs in pitch or measure from the spacing of the primary gage, and a plunger for engaging said teeth to shift the rack 65 when the latter is located in accordance with the setting of the primary gage.
17. In a type casting machine, the combination of the following elements, to wit: A movable die-case and movable carrier therefor, two centering or positioning mechanisms connected respectively to the die case and carrier and each controlled by a signal-responsive gaging mechanism, an auxiliary gaging mechanism, connected with the die-case or its carrier and controlled by the two signal-responsive gaging mechanisms, the one for action and the other for selective operation.
18. A type casting machine provided with a movable die case, a transversely movable carrier and two centering or positioning mechanisms connected to the die-case and carrier, respectively, and each controlled in its positioning action by a signal-responsive gaging mechanism, and, in combination therewith, an auxiliary gaging mechanism whose pitch or measure differs from that of the aforesaid centering or positioning mechanism, said auxiliary gaging mechanism being connected with one centering or positioning mechanism to vary the position of the member actuated thereby, and controlled by the other centering or positioning mechanism to determine the time of application of 95 said auxiliary gaging mechanism.
19. A centering or positioning mechanism such as described provided with a movable member subject to the control of signal responsive gaging devices, and in combination therewith, an auxiliary gaging mechanism of different pitch or measure operating in conjunction with the signal responsive gage to determine different positions of adjustment according to the pitch or measure of 105 said auxiliary gaging mechanism, and means under control of the signal responsive gaging mechanism for automatically shifting control of the movable member from the signal responsive gage alone to the auxiliary 110 and signal responsive gages acting in conjunction.
20. A centering or positioning mechanism equipped with an adjustable member and positioning means therefor, primarily controlled by signal-responsive gaging devices, and in combination therewith, an auxiliary gaging mechanism, the pitch or measure whereof differs from that of the signal responsive gaging devices, said auxiliary gaging mechanism acting in conjunction with the signal controlled responsive gaging devices to locate the adjustable member in any of the positions indicated, and controllable means for cutting in and out said auxiliary 120 gaging mechanism.
21. A centering or positioning mechanism provided with an adjustable member whose

position is primarily determined by a signal controlled gage of predetermined pitch or measure, and in combination therewith, an auxiliary gaging mechanism of different pitch or measure coupled with said adjustable member and acting in conjunction with said signal controlled gage to locate the adjustable member in any of the different stations indicated by said auxiliary gaging mechanism.

22. In a centering or positioning mechanism for type casting machines, the combination of the following elements, to wit: a signal controlled gage; oppositely movable jaws whose closed position is determined by said gage; a movable member intermediate said jaws and positioned thereby; a rack coupled with said movable member, the teeth whereof are spaced to a different measure from the signal controlled gage; and a plunger located at a fixed point in the line of movement of said rack and movable into engagement with the latter to transform the adjustment from a station indicated by the signal controlled gage into one of the series of stations indicated by the rack teeth.

23. In a centering or positioning mechanism for type casting machines, the combination of the following elements, to wit: a signal controlled gage; oppositely movable jaws whose closed position is determined by said gage; a movable member projecting between said jaws and positioned thereby, and an auxiliary gage coupled with said movable member and provided with a series of gaging members whose pitch or measure differs from that of the signal controlled gage, and an engaging member located at a fixed point in the line of travel of said auxiliary gage and coöperating therewith to vary the position of the movable member as determined by the signal controlled gage.

24. In a point-to-point centering or positioning mechanism including a signal controlled gage, oppositely movable jaws, and a movable member, and in combination therewith, a supplemental or auxiliary gaging mechanism including a rack coupled with said movable member, and provided with a series of teeth or inclines, the pitch or measure whereof differs from that of the signal controlled gage, and a plunger adapted to engage said teeth or inclines, and shift 55 the position of the rack.

25. In a type casting machine, provided with a die case and a carrier therefor movable on intersecting lines, and a plurality of positioning or centering mechanisms, one 60 for the die case and the other for its carrier, each of said positioning mechanisms including a signal controlled gaging means of a predetermined pitch or measure, and in combination therewith, two auxiliary gaging means, one for each positioning or centering

mechanism, each of said auxiliary gaging means including a gaging member whose pitch or measure differs from that of the associated signal controlled gage and is set by the associated positioning mechanism, and 70 a plunger coöperating with said gaging member to displace the latter in a predetermined degree from the station otherwise indicated by the signal controlled gaging means.

26. In a centering or positioning mechanism for performing members of a type casting machine, the combination of the following elements, to wit: a principal positioning mechanism including signal controlled gaging means operating through positioning devices to locate or set the performing member at any one of a series of stations; and an auxiliary gaging mechanism including a gaging member provided with a series of 80 inclines, the pitch or spacing whereof differs from that of the signal controlled gaging means, and a coöperating plunger, said gaging member being connected to the performing member and receiving its set from 90 the signal controlled gaging means of the principal positioning mechanism.

27. In a type casting machine, the combination of the following elements to wit: a die case and centering or positioning mechanism therefor including signal controlled gaging means for designating successive stations; an auxiliary gaging means whose pitch or measure differs from that of the first named gaging means and includes complementary members whereof one receives its setting from the signal controlled gaging means and is in turn set by the other member of the pair, and means for transmitting the final setting of the auxiliary gaging devices to the die case.

28. In a type casting machine provided with a movable die case and a centering or positioning mechanism therefor including signal controlled gaging members, translating devices and positioning means under the control of said gaging members for shifting the die case directly from one signal indicated position to the next, and in combination therewith, an auxiliary gaging mechanism whose pitch or measure differs from that of the signal controlled gaging members, the same including complementary members whereof one is coupled with, so as to receive its set from, the signal controlled 110 gaging members, and is provided with a series of spaced gaging inclines, and the other is held from motion in the direction of motion imparted to the first named member, but is movable transversely thereof to 115 vary the set of said gaging member as derived from said signal controlled gaging members.

29. In a centering or positioning mechanism, the combination with a principal gag- 130

ing mechanism including signal controlled gaging members, an adjustable member and positioning devices for the latter under the control of said gaging members, of an auxiliary gaging mechanism differing as to pitch or measure from that of the principal gaging mechanism and including two relatively movable members whereof one is provided with spaced gaging members and the other 5 an engaging member, one of said members being coupled with the principal gaging mechanism and receiving its set from the signal controlled gaging members thereof, and the other movable into engagement with 10 said shiftable member to shift the latter and bring it into register with the indicated 15 station of the auxiliary gaging mechanism.

30. In a centering or positioning mechanism such as described, the combination of 20 the following elements, to wit: a gaging mechanism including a movable member, positioning means therefor and signal-responsive gaging devices acting through the 25 positioning means to locate the movable member at any one of the series of stations represented by the gaging devices; an auxiliary gaging mechanism including an admeasuring member coupled with the aforesaid movable member and provided with a 30 series of inclines whose pitch or measure differs from that of the signal responsive gaging devices, and a positioning plunger; and means for actuating said positioning 35 plunger to engage the admeasuring member of the auxiliary gaging mechanism, when

the movable member of the principal gaging mechanism has been brought to a signal designated position.

31. A centering or positioning mechanism provided with signal controlled gaging 40 means for designating successive stations, and in combination therewith, an auxiliary gaging means differing in pitch or measure from the first named gaging means and controlled through the latter to translate 45 designating signals pertaining to the first named gaging means into signals of the auxiliary gaging means.

32. In a centering or positioning mechanism for type casting machines, the combination of the following elements, to wit: a plurality of gaging systems differing as to pitch or measure, and signal responsive controlling devices common to the several gaging systems for designating stations in either 55 of the latter.

33. In a centering or positioning mechanism, such as described, provided with signal controlled gaging means, and in combination therewith, a supplemental or auxiliary gag- 60 ing means of different pitch or measure from the first named and acting in conjunction with the latter to translate signals pertaining to one gaging system into those of the other system.
